UNITED STATES PATENT OFFICE.

SARAH H. PECKHAM, OF NEW YORK, N. Y., ASSIGNOR TO HANKS GASOLENE METER CO., OF NEW YORK, N. Y., A CORPORATION OF NEW YORK.

INDICATOR FOR LIQUID-FUEL TANKS.

No. 923,073.

Specification of Letters Patent.

Patented May 25, 1909.

Application filed November 5, 1907. Serial No. 400,847.

To all whom it may concern:

Be it known that I, SARAH H. PECKHAM, a citizen of the United States, and a resident of the city of New York, borough of Manhattan, 5 in the county of New York and State of New York, have invented certain new and useful Improvements in Indicators for Liquid-Fuel Tanks, of which the following is a specification.

10 This invention relates to improvements in indicators for liquid fuel tanks such as are used for example on automobiles, on launches or the like.

15 The object of my invention is to provide a new and improved indicator of this kind, which is positive and reliable in action and prevents the indicator from being operated by the jolts or other sudden up and down movements of the vehicle or vessel containing the tank.

20 In the accompanying drawings, in which like numerals of reference indicate like parts in all the figures: Figure 1 is a vertical longitudinal sectional view of a liquid fuel tank 25 containing my improved indicator. Fig. 2 is a plan view of part of the same, parts being in section. Fig. 3 is a detail view.

25 In the fuel tank 1 which may be of any desired construction a rock shaft 2 is mounted horizontally, at about half the height of the tank, which rock shaft carries a toothed sector 3, engaging a pinion 4 on the lower end of a vertical rock shaft 5, projecting from the top of the tank and operating an indicator 6 of any suitable construction with or without a registering device, for example, such as shown in my pending application, Ser. No. 384,259, filed July 17, 1907. An arm 7 secured on the rock shaft 2 is pivotally connected with a flat float 8 provided with a recess 9. A ratchet bar 10 curved on the axis of the rock shaft 2 as a center is rigidly secured vertically within the tank. A pawl 11 pivoted to the bar 7 at 12 is provided at its 40 lower end with a weight 13 for keeping the opposite end of the pawl in engagement with the ratchet bar 10. A bar 14 curved on the same radius as the bar 10 is provided at its lower end with a horizontal arm 15 which is pivoted at 16 to the bottom of the tank so that this bar 14 can be swung toward and from the back of the ratchet bar 10 and the weight 13 on the lower end of the pawl 11 projects across the inner edge of the pivoted

5 curved bar 14 as shown clearly in Fig. 2. The bar 14 is provided at its upper end with an arm 17 terminating in a socket 18 which is beneath the screw neck 19 of the filling opening of the tank, which screw neck can be closed by a screw plug 20 and this screw plug 60 is provided on its underside with a flaring neck 21, that is a neck in the shape of a frustum of a cone. The socket 18 is provided with beveled lugs 22 and 23 the bevels of which are parallel.

65 When the plug 20 is unscrewed from the screw neck 19 so as to permit of filling the tank, the upper heavier end of the bar 14 is released and causes said bar to swing into the position shown in dotted lines in Fig. 1, 70 whereby by the action of the rear edge of the curved bar 14 on the weight 13, said weight is lifted and the pawl 11 is disengaged from the ratchet bar 10 thus permitting the float to rise as the level of the liquid rises in the 75 tank, as the supply of liquid fuel is filled in.

When the tank is full the plug 20 is screwed into the neck 19 and its beveled neck 21 acting on the beveled edge of one of the lugs of the socket 18 swings said bar 14 to the right 80 and into the position shown in full lines, thus permitting the weight 13 to drop and to bring the pawl 11 into engagement with the ratchet bar 10. As the level of the liquid gradually decreases in the tank as the liquid 85 fuel is consumed, the float descends, which descent is not interfered with by the pawl 11 as the latter slides down over the teeth of the ratchet bar. The jolting of the vehicle and consequent disturbing of the level of the 90 liquid cannot cause the float to rise as the pawl 11 prevents this and any upward movement of the float is checked by the engagement of the pawl with the teeth of the ratchet bar. The indications on the scale or indicator 95 9 are thus at all times true and reliable. If provision were not made for preventing the float from moving up and down under the action of the jolting of the vehicle, the indicator would be caused to operate every time 100 that the vehicle was jolted and thus the indications would not be correct, as they would necessarily count up a greater quantity of liquid fuel than had been actually consumed.

Having described my invention what I 105 claim as new and desire to secure by Letters Patent is:—

1. The combination with a liquid fuel tank,

a float in the same, an indicator, and means for operating the indicator by the float, of means for temporarily and automatically suspending upward movement of the float at any point of the elevation between the top and bottom of the tank, substantially as set forth.

2. The combination with a liquid fuel tank, a float and an indicator and means for operating it by the float, of means for temporarily suspending upward movement of the float, and means whereby the temporary suspending means can be thrown out of operation, substantially as set forth.

3. The combination with a liquid fuel tank, a float, an indicator and means for operating it by the float, of means for temporarily suspending the upward movement of the float, and means for throwing the temporary suspending means out of operation, substantially as set forth.

4. The combination with a liquid fuel tank having a filling opening, a float in the same, an indicator and means for operating it by the float, of means for temporarily preventing upward movement of the float, means for opening and closing the opening of the tank and means for throwing said temporary preventing means into and out of operative position by closing and opening the supply inlet of the tank, substantially as set forth.

5. The combination with a liquid fuel tank having a filling opening, a float in the same, an indicator and means for operating it by the float, of means for temporarily preventing upward movement of the float, a plug for closing the filling opening of the tank, and means for throwing the float checking means into and out of operative position by operating said plug, substantially as set forth.

6. The combination with a liquid fuel tank, a float in the same, an indicator and means for operating it by the float, of a ratchet bar in the tank, a pawl normally engaging said ratchet bar and connected with the float, and means for throwing said pawl into and out of engaging position with the ratchet bar, substantially as set forth.

7. The combination with a liquid fuel tank having a filling opening, a float in the same, an indicator and means for operating it by the float, of a ratchet bar in the tank, a pawl normally engaging said ratchet bar and connected with the float, a plug for closing the filling opening of the tank, means controlled by the plug for the filling opening of the tank, for throwing said pawl into and out of engaging position with the ratchet bar, substantially as set forth.

8. The combination with a liquid fuel tank, a float in the same, an indicator and means for operating the same by the float, of a ratchet bar in the tank, a pawl on the float normally engaging the ratchet bar, a movable bar adjacent to the ratchet bar and

adapted to throw the pawl into and out of engaging position with the ratchet bar, substantially as set forth.

9. The combination with a liquid fuel tank, a float in the same, an indicator and means for operating it by the float, of a ratchet bar in the tank, a pawl on the float normally engaging the ratchet bar, a pivoted bar adjacent to the ratchet bar and adapted to throw the pawl into and out of engaging position with the ratchet bar, substantially as set forth.

10. The combination with a liquid fuel tank having a filling opening, a float in the same, an indicator and means for operating it by the float, of a ratchet bar in the tank, a pawl on the float normally engaging the ratchet bar, a movable bar adjacent to the ratchet bar and adapted to throw the pawl into and out of engaging position with the ratchet bar, a plug for closing the filling opening of the tank and means on said plug for controlling the movement of said movable bar toward and from the ratchet bar, substantially as set forth.

11. The combination with a liquid fuel tank having a filling opening, a float in the same, an indicator, and means for operating it by the float, a ratchet bar in the tank, a pawl on the float normally engaging the ratchet bar, a pivoted bar adjacent to the ratchet bar and adapted to throw the pawl into and out of engaging position with the ratchet bar, means for opening and closing the tank filling opening and for controlling the movement of said bar adjacent to the ratchet bar operable by operating the filling opening and closing means of the tank, substantially as set forth.

12. The combination with a liquid fuel tank having a filling opening, a float in the same, an indicator, and means for operating it by the float, of a ratchet bar in said tank, a pawl on the float normally engaging said ratchet bar, a movable bar adjacent to the ratchet bar and adapted to act on the pawl, to bring the same into and out of operative position with the ratchet bar said movable bar being provided at its upper end with a bevel socket, and a filling plug having beveled projections fitting said socket, substantially as set forth.

13. The combination with a liquid fuel tank having a filling opening, a float in the same, an indicator, and means for operating it by the float, a ratchet bar in the tank, a pawl pivoted on the float normally engaging the ratchet bar, a movable bar adjacent to the ratchet bar, a projection on the pawl engaging one edge of the movable bar, means for controlling the filling opening of the tank, and for controlling the movement of said movable bar operable by operating said opening controlling means for the purpose of bringing the pawl into and out of engaging

position with the ratchet bar, substantially as set forth.

14. The combination with a liquid fuel tank having a filling opening, a float in the same, an indicator and means for operating it by the float, of a ratchet bar in the tank, a pawl pivoted on the float and normally engaging the ratchet bar, a movable bar adjacent to the ratchet bar, a projection on the 10 pawl engaging one edge of the movable bar, a beveled socket in the upper end of the movable bar, a plug for closing the filling opening of the tank, which plug has a projection fitting said socket, substantially as set forth.
15. The combination with a liquid fuel tank having a filling opening, a rock shaft in the same, an arm on said shaft and a float on 20 said arm, of a ratchet bar curved on a radius, the center of which is the axis of the rock shaft, a pawl on the float normally engaging said ratchet bar, means for opening and closing the filling opening of the tank, and means for disengaging said pawl from the ratchet operable by opening the filling opening of the 25 tank and for engaging said pawl with the ratchet bar by closing the filling opening in

the tank and an indicator, which is operated from the float, arm and rock shaft substantially as set forth.

16. The combination with a liquid fuel tank having a filling opening, of a rock shaft in the same, an arm on said rock shaft, a float on said arm, a ratchet bar held in the tank and curved on a radius, the center of which is the axis of the rock shaft, a pawl piv- 30 oted on the float, a pivoted bar adjacent to the curved rack bar, and curved on the same radius, means for opening and closing the filling opening of the tank, and for swinging said bar toward and from the rack bar operable 35 by the act of operating the closing and opening means for the opening of the tank, an indicator and which is operated from the float, arm and rock shaft substantially as set forth.

Signed at New York city in the county of 40 New York and State of New York this 31st day of October A. D. 1909.
